IMPELLING MECHANISM FOR FEEDING AND CUTTING

Frank H. Mayoh, Springfield, Mass.

Application April 12, 1932. Serial No. 604,754

16 Claims. (Cl. 164—56)

This invention relates to a mechanism for performing feeding and cutting or like operations on paper, cloth, strip metal or similar material, and has for its object the production of new and improved type, wherein a new mechanical device, is operated by a new and novel impelling system.

One object of the present invention is to operate feeding rolls intermittently for variable periods to permit the cutting off of sheets to predetermined lengths.

Another object is the provision of a yieldable drive to start the feed mechanism smoothly and in like manner the roll of material being operated upon.

Another object is the provision of a clamp and cut-off mechanism of a type that will hold and sever a great variety of materials.

Another object is the provision of mechanism to convey the sheets cut-off away.

Another object is the provision of a system of impellation whereby the functions of various mechanisms are controlled by the displacement of fluids in a hydraulic system.

Still another object is the provision of a mechanism that can be operated as an independent unit or that can be attached for the purpose specified to a variety of machines, such as folding machines, printing presses, metal working machines or wrapping machines as examples of diverse use.

Other objects and advantages will appear from the following description of one embodiment of the invention.

In the drawings, which are merely a preferred form of the invention.

Fig. 1 is a side elevation of the entire mechanism.

Fig. 2 is a front elevation of that portion of the entire mechanism to the left of 15 on line 2—2 of Fig. 1.

Fig. 3 is a plan section showing that portion of the entire mechanism below line 3—3 of Fig. 2.

Fig. 4 is a section through the feed roll drive on line 4—4 of Fig. 1 on an enlarged scale.

Fig. 5 is an end view of the mechanism shown in Fig. 4 with the outer housing 43 removed.

Fig. 6 is an end view of the adjustable cam shown in Fig. 2 in the direction 6—6.

Fig. 7 is an end view of a cam shown in Fig. 2 in the direction 7—7.

Fig. 8 is an end view of the drive sprocket unit in the direction 8—8 of Fig. 2.

Fig. 9 is a section taken through line 9—9—9 of Fig. 8.

Like numbers designate like parts throughout the several views of the drawings.

The present embodiment of the invention comprises a feed roll 1, that co-acts with a tension roll 2 to feed strips of paper or other material from a roll 3 this roll of material may be paper, cloth, imitation leather, cellophane, strip metal or similar material in kind and said material could be fed from a box or rack in stock lengths as well as from a roll. Tension roll 2 revolves on shaft 4, mounted in two levers 5 that pivot on studs 6 in bosses on the frame of the device. Roll 2 is in running contact with feed roll 1, and as the material is fed between rolls 2 and 1 by the revolving of roll 1, in the direction of arrow 7 the strip of material 8 is fed through the rolls so that it will pass over three belts indicated at 9. A frame 10 comprising sides 11 and 12 with a cross section at 13 and 14 provides the major structure in which this entire mechanism is mounted and at 15 is indicated a structure representative of any type of machine to which this entire feeding and cutting unit may be attached by means of screws 16. The machine structure may be one of several types requiring a feeding mechanism such as are commonly used in paper converting, cloth or metal working industries. The material operated on is taken from roll 3, it travels along line 17 over roll 1, and is delivered in cut sheets at 8, roll 3 revolves in the direction 85 of arrow 20.

In contact with the roll of material is a pressure roll 18 that is free to travel of its own weight along slots 19 in the sides 11 and 12 of frame 10. This roll 18 keeps a constant pressure on the material thereby acting as a break and preventing the roll of material from unwinding except as the material is fed by the rolls 1 & 2.

A main shaft 21 is driven by means of a chain 22 and sprocket 23 (pinned in place) from a drive shaft within the machine that this mechanism forms a part of, or from a motor if the mechanism is used alone for the simple purpose of feeding and cutting. As shaft 21 revolves in the direction of arrow 24 sprocket 25 is revolved and this drives chain 26. Sprocket 25 is preferably constructed as shown in Figs. 8 and 9 so that it will yieldably take up the load of feeding as it is applied. To provide this yielding action I have mounted within the sprocket 25 a sleeve 27 with two lugs 28 as an integral part thereof, this sleeve 27 is keyed to shaft 21 to 29 and revolves as a part thereof, two springs 30 are placed in retaining recesses in the sprocket 25, said sprocket being otherwise free to rock on the sleeve within limits 110

as described in the following paragraph. A flange 31 attached by screws 32 holds the sprocket springs in place while a collar 33 holds the entire unit on the end of the shaft.

5 As sprocket 25 picks up the load in starting the feeding, springs 30 are compressed against lugs 28 Fig. 8 and the recess due to the clockwise revolving action of shaft 21 until the feeding of roll 1 commences following which the load becomes 10 lighter and the springs expand to their near normal position ready for the initial shock of starting the next cycle of feeding, which yielding action provides a smooth flexible pick up for the feeding of the material operated on and one that 15 also allows a gradual deceleration of the feeding roll as the feed mechanism is stopping and the load is removed.

As chain 26 is driven continuously by sprocket 25 it transmits movement continuously to another 20 sprocket 34 mounted on the outer end of a shaft 35 to which the feed roll 1 is attached. Shaft 35 revolves in two bearings that are made an integral part of frame 10 and this shaft 35 revolves only when it is desired to feed roll 1 which is 25 during a variable portion of each complete cycle of the entire mechanism comprising the feeding and cutting or other sequence of operations. To accomplish this a novel type of clutch is provided the operation of which will be best understood by 30 referring to Figs. 4 and 5.

In sprocket 34 is mounted a split ring 36 having beveled surfaces 37 at the split which contact with a bevel point on pin 38, pin 38 also has a bevel at the opposite end that contacts with a 35 corresponding bevel on a lengthwise movable pin 39 having a large head as part thereof. Ring 36 is tempered so that it springs inward and contracts in diameter, normally this causes pin 38 to be pushed towards the center of shaft 35, this 40 also causes pin 39 to be forced to the left as shown in Fig. 4 although I have shown in addition a spring 40 to assist in the movement of pin 39. Due to this inward contraction of split ring 36 sprocket 34 is free to revolve on a bushing 41 45 pinned at 42 to shaft 35, therefore shaft 35 is not revolved and in consequence there will be no revolving of the feeding roll 1, except as provided for through the action of a hydraulically operated medium that pushes against the head of 50 pin 39 thereby causing the bevel surfaces to force pin 38 outward radially which expands ring 36 and causes said ring to grip frictionally sprocket 34 within the hole said ring is mounted in, thereby causing shaft 35 to revolve and operate roll 1 55 to feed the paper or material being operated on.

Over the outer end of shaft 35 (Fig. 2) is a housing 43 secured to frame 10 by two studs 44, attached to housing 43 is a hollow pipe 45, the other end of this pipe (made continuous by inserting a union and elbow) is attached to a boss 46 in the frame, inside of boss 46 is a plunger 47, this carries a roll 48 mounted on a pin 49. Roll 48 is always in contact with an adjustable cam made in two sections 50 and 51, the function of 60 this cam which is pinned to shaft 21 is to force plunger 47 up at the proper time in the operative cycle of the entire mechanism, this in turn causes a fluid substance (preferably oil) that is retained in the upper chamber of boss 46 above the plunger 47 and in the pipe 45 to press against pin 39 and thereby causing ring 36 to expand and cause sprocket 34 to revolve the feeding roll as previously described.

When the cam allows plunger 47 to go down 75 the fluid substance is likewise pushed down by

the expanding spring action of pin 39 which disengages the frictional contact of the split ring 36 and allows the feed roll to stop. The construction of the fluid impelling cam will be evident by referring to Fig. 6 where that portion of it 50 is pinned to shaft 21 the other portion 80 51 is free to pivot about the shaft as a center and is locked at various points by a lock screw 52, the object of this adjustment is to vary the length of the radius 53 as compared to the radius 54 so that plunger 47 in Fig. 2 may be held up for a greater or less length of operating time through 85 each cycle of the mechanism so that a greater or less length of paper may be fed by the feed rolls past the cutting off knife (which is indicated as 90 55) during each operation of the knife which is caused to cut the paper once during each cycle of the machine.

Knife 55 is held by four screws 56 to a slide bar 57, this bar is free to move up and down on two posts 58. In this bar are slidably mounted six pins 59 the lower ends of which clamp the paper as it is cut-off there being three pins at the front of the knife and three at the rear of the knife. Bent wire springs 60 held in place by 95 screws 61 cause the pins to extend down below the cutting edge of the knife previous to the cutting operation and the first thing that happens as slide bar 57 descends is for the clamp pins 59 to grip the paper or material operated on at the 100 front and rear of the cutting knife 55, the clamping action taking place against long bars 62 and 63 at the front and rear of the knife respectively underneath the paper except that at the rear there is a long flat spring 64 the front end of 105 which is over the rear bar 63, consequently the rear end of the material cut off is clamped against this spring 64 the reason for which will appear in the next paragraph. Two screws 65 hold the long bars in place while the flat spring is held 110 to the frame structure by screws at 66, the bars are arranged so there is a slot between them for the knife to pass through.

Briefly described what takes place in cutting off is that as slide bar 57 descends, clamp pins 59 115 grip the material and as slide bar 57 continues down knife 55 is forced through the material thereby cutting it off, following this the clamp pins 59 are carried up by the slide bar to release the paper, at that time there is a slight upward 120 spring action to the flat spring 64 which insures that the free end of the material to be fed will be slightly above bar 62 as it is fed forward during the next cycle of the entire mechanism. The strip of paper cut off is passed between a 125 pair of rolls 67 and 68 the lower of which 67 is driven at a speed faster than that at which the paper is normally fed by the feed rolls, through the medium of the three belts 9 which are caused to travel by three pulleys 69 shown on the lower 130 drive shaft 21. There are also three outer pulleys 70 held within a co-acting machine at any suitable place where it is desired to carry the paper in, these being merely idle pulleys over which the conveying belts 9 travel. Roll 68 is free to 135 move up and down in its supporting brackets 71 and of its own weight it acts as a tension roll to assist in carrying the sheet cut-off away. To cause slide bar 57 to move down hydraulical 140 actuating mechanism is employed while two 145 springs 72 force the slide bar up at the completion of the cut.

In each of the two slide bar guide posts 58 are drilled two holes, one hole lengthways of the post the upper end of which is plugged by a 150

5 screw 73 and the other crossways of the post as indicated at 74 in both posts, there is also a chamber at 75 which is filled with oil or other fluid substance, which fluid also fills the post holes and in addition pipe 76 connecting both posts together with a co-acting pipe 77, all of said pipe being joined by elbows or other standard pipe fittings. Pipe 77 leads to a chamber 81 above plunger 78 in boss 79 of the frame and 10 as cam 80 forces plunger 78 up as shaft 21 revolves said cam thus forces the hydraulic fluid in the pipes 77 and 76 into the two chambers 75 and forces slide bar 57 down, which in turn causes knife 55 to perform the function of cutting off.

15 An end view of the plunger cam 80 is shown in Fig. 7 this shows a long dwell and a bump at 82, in operation as this cam revolves the bump 82 quickly forces plunger 78 up thereby impelling the hydraulic fluid to perform the clamping and cutting off operation while the two springs 72 hold the knife slide bar up during the long dwell when plunger 78 is down. There is a roll 83 revolving on pin 84 interposed between the plunger and cam. Screws at 73 and at 85 are used to 20 plug the filling hole where the fluid is put in place.

25 To review briefly the operation of this feeding and cutting mechanism it is obvious that a roll of material 3 with a pressure roll 18 against it is fed through feed roll 1 and tension roll 2. Roll 1 is caused to revolve through the action of the adjustable cam pushing a fluid substance through pipe 45 and causing a clutch arrangement to drive said roll 1, when the desired length of material is fed out the clutch arrangement is released by removing the fluid pressure thereby stopping feed roll 1, after which another hydraulic fluid unit operates knife slide bar 57 so that the material is clamped and cut off, after 30 the knife 55 and clamp pins 59 go up the material is again fed out while through the medium of speed belts 9 the sheet cut-off is carried away from this unit or into any suitable machine that this unit is a part of.

35 It will be understood that the specific form of the improvement described and shown is illustrative of my invention, and that changes may be made in the impelling medium or mechanism within the scope of the claims as occasion demands without departing from the spirit of the invention.

40 I claim:—

1. Mechanism for feeding and severing sheets from a continuous strip of web material comprising means for feeding the material strip endwise, a cutting device, means for actuating said cutting device and means to control said feeding mechanism intermittently embracing in combination fluid and mechanical impelling contacts 45 adapted to displace said fluid to perform the operating sequence.

2. Mechanism for feeding and severing sheets from a continuous material strip comprising means for feeding the material strip endwise, a cutting device, means for actuating said cutting device and means to control said feeding mechanism intermittently embracing confined flexible concentrates and mechanical impelling devices.

3. In a continuous web material cutting device, 50 a material feed roll and a gripping roll co-engaging therewith, a retaining support to hold a roll of material, a material clamp mechanism, a cutting knife, means to operate said knife comprising a combined hydraulic and mechanical actuating system, a hydraulic system terminating in a

mechanical actuating mechanism to cause said feed roll to operate, a feeding drive unit embracing a flexible drive for said feed roll comprising in combination a driven housing and a yieldable drive member adapted to retard momentarily the feed 55 action at the start of each feeding cycle.

4. In a continuous web material cutting device, a material feed roll, a retaining support to hold a roll of material, a system of material clamps, a cutting knife, means to operate said knife comprising a hydraulic actuating system and mechanical impelling contacts therefor, and a hydraulic system terminating in mechanical actuating mechanism operating said feed roll.

5. In a continuous web material cutting device, a material feed roll, a retaining support to hold a roll of material, a cutting knife, means to operate said knife comprising a hydraulic actuating system mechanically impelled and a hydraulic system mechanically impelled terminating in 95 mechanism operating said feed roll.

6. A machine unit of the character described in combination with, a continuous web material feed device, means comprising in combination a hydraulic and mechanical impelling system actuating said feed device, and a cutting knife and material clamp jointly operable by means including hydraulic with mechanical impelling mechanism as part thereof.

7. A machine unit of the character described in combination with, a continuous web material feed device, means comprising a hydraulic system mechanically impelled actuating said feed device, and a cutting knife operable by means including a combined mechanical and hydraulic impelling 105 mechanism as part thereof.

8. A machine for feeding and cutting off from a continuous strip of web material having in combination a retaining support to hold a roll of material, a feeding roll, a friction drive for said feeding roll, a yielding drive sprocket adapted to retard momentarily said feeding roll at the start of a feeding cycle, a cutting-off knife and reciprocating support therefor, operating means for said knife and roll embracing as part thereof a 110 drive and hydraulic system with mechanical actuators to impel intermittently said feed roll and knife.

9. A machine for feeding and cutting off embracing in combination a cut-off knife and operating mechanism therefor, a feeding unit embracing a flexible drive for said feeding unit comprising in combination a driven housing and a yieldable drive member adapted to retard momentarily the feeding action at the start of each 115 feeding cycle.

10. Mechanism for severing sheets from a continuous strip of web material comprising means for feeding the material strip endwise, a cutting device having a movable element, a pressure fluid confined in a chamber and means for actuating the cutting device embracing in combination a pumpless mechanical impelling contact adapted to intermittently displace at intervals said fluid associated with a plural function coacting 130 mechanism operating the fluid impelling contact.

11. Mechanism for severing sheets from a continuous material strip comprising means for feeding the material strip, a cutting device having a movable element, a confined flexible concentrate constantly active under a non-reducible pressure and co-acting with means for actuating said cutting device embracing in combination a pumpless mechanical impelling contact adapted to intermittently operate at synchronized inter- 145

vals in association with a plurality of automatic mechanisms adapted to intermittent propulsion.

12. A mechanism for cutting off having in combination, a cut-off knife and support therefor, an operating means for said knife embracing jointly an enclosed flexible impelling concentrate in combination with a pumpless mechanical impelling device having intermittent propulsion means adapted to intermittently actuate said knife so that each action of the knife is responsive to each action of the intermittent impelling device.

13. Mechanism for feeding a continuous strip of web material comprising means for feeding the material, means for actuating the strip feeding mechanism periodically having a movable element and a constant pressure fluid confined constantly in a chamber and means associated therewith for actuating said fluid periodically embracing a pumpless mechanical impelling contact as a motive force to cause the feeding mechanism to operate.

14. Mechanism for feeding a continuous strip comprising means for feeding the material, means for actuating the strip feeding mechanism periodically having a movable element and a constantly confined flexible concentrate and means associated therewith for actuating intermittently

the same said flexible concentrate embracing a pumpless mechanical impelling contact as a motive force to cause the feeding mechanism to operate.

15. A mechanism for driving between a source of power and an operative mechanism having in combination, a friction drive unit intermittently actionable, means for actuating the friction drive periodically having a movable element and an impelling concentrate confined constantly under constant pressure and means associated therewith for actuating periodically said impelling concentrate embracing a pumpless mechanical impelling contact adapted to cause said friction to engage to impart movement.

16. A mechanism for controlling action between a source of power and an operative mechanism having, a movable element comprising an impelling concentrate confined constantly under constant pressure and means associated therewith for actuating periodically said impelling concentrate embracing a pumpless mechanical impelling contact adapted to intermittently cause said operative mechanism to move at periodically controlled intervals for the purpose of creating a unison of movement between said source of power and said operative mechanism.
